UNITED STATES PATENT OFFICE

170,389

FISHING REEL

Henry G. Shakespeare and Gerald D. Harrington,
Kalamazoo, Mich., assignors to Shakespeare
Company, Kalamazoo, Mich., a corporation of
Michigan

Application December 3, 1951, Serial No. 17,594

Term of patent 14 years

(Cl. D31—4)

To all whom it may concern:

Be it known that we, Henry G. Shakespeare and Gerald D. Harrington, citizens of the United States, residing at Kalamazoo, county of Kalamazoo, and State of Michigan, have invented a new, original, and ornamental Design for a Fishing Reel, of which the following is a specification, reference being had to the accompanying drawing, forming a part hereof.

Fig. 1 is a side elevational view.

Fig. 2 is a top plan view.

Fig. 3 is a rear end elevational view of a fishing reel, embodying our new design.

We claim:

The ornamental design for a fishing reel, as shown.

HENRY G. SHAKESPEARE.
GERALD D. HARRINGTON.
